Primary Examiner — Terry Wallace*(74) Attorney, Agent, or Firm* — Maschoff Brennan(57) **CLAIM**

The ornamental design for a container with lid, as shown and described.

DESCRIPTION

FIG. 1 is a front elevation view of the container with lid (the rear elevation view is symmetrical to the front elevation view);

FIG. 2 is a left, side elevation view thereof (the right, side elevation view is symmetrical to the left, side elevation view); FIG. 3 is a top plan view thereof;

FIG. 4 is a bottom plan view thereof where the broken lines depicting an exemplary contour of the bottom of the container form no part of the claimed design; and,

FIG. 5 is a perspective view thereof.
